COMBINED FLASHLIGHT AND UNIVERSAL FUSE TESTER

Joe L. Alexander, Puryear, Tenn., assignor to A-G
Products, Inc., Paducah, Ky., a corporation of Ken-
tucky

Filed July 27, 1964, Ser. No. 81,006

Term of patent 14 years

(Cl. D26—1)

FIG. 1

FIG. 2

FIG. 3

FIG. 4

FIG. 5

FIG. 6

FIG. 7

FIG. 8

FIG. 1 is a perspective view of a combined flashlight and universal fuse tester, showing my new design;

FIG. 2 is a top plan view;

FIG. 3 is a front elevational view;

FIG. 4 is a rear elevational view;

FIG. 5 is a right end elevational view;

FIG. 6 is a left end elevational view;

FIG. 7 is a bottom plan view; and

FIG. 8 is a cross-sectional view, partly in elevation, taken on line 8-8 of FIG. 2.

The broken line showing of a removable flashlight battery in FIG. 7 is for illustrative purposes only.

I claim:

The ornamental design for a combined flashlight and universal fuse tester, as shown.
